A. M. LANE.

FRUIT TRAY.

APPLICATION FILED SEPT. 30, 1918.

1,310,800.

Patented July 22, 1919.

THE COLUMBIA PLANOGRAPH CO., WASHINGTON, D. C.

UNITED STATES PATENT OFFICE.

ALFRED M. LANE, OF ST. LOUIS, MISSOURI, ASSIGNOR TO MONARCH METAL WEATHER STRIP COMPANY, OF ST. LOUIS, MISSOURI, A CORPORATION OF MISSOURI.

FRUIT-TRAY.

1,310,800.

Specification of Letters Patent.

Patented July 22, 1919.

Application filed September 30, 1918. Serial No. 256,200.

To all whom it may concern:

Be it known that I, ALFRED M. LANE, a citizen of the United States, and a resident of the city of St. Louis and State of Missouri, have invented a new and useful Improvement in Fruit-Trays, of which the following is a specification.

This invention relates to sheet metal trays for drying fruits and particularly to trays with removable openwork bottoms adapted for facilitating the ventilation of the fruit. The principal objects of the invention are to produce a strong, rigid, lightweight tray of simple construction, which can be cheaply manufactured; to reduce the number of parts of the tray, and to provide for the easy assemblage of these parts; to facilitate the attachment and detachment of the removable openwork bottom; and also to provide a means for stretching the removable openwork bottom over the tray frame and for securing the bottom in its stretched position to the tray frame.

The invention consists in the parts and arrangements of parts hereinafter more fully described and claimed.

In the accompanying drawing, which forms part of this specification and wherein like symbols refer to like parts wherever they occur,

Figure 1 is a plan view of a fruit tray embodying my invention;

Fig. 2 is a side elevation of the tray;

Fig. 3 is an enlarged cross-sectional view of the marginal portion of the tray;

Fig. 4 is a cross-section view showing the parts of the tray in position to be assembled;

Fig. 5 is a side elevation of the strip and bar which form the frame of the tray before these members are bent into the desired shape; and

Fig. 6 is a side elevation of the clamping strip before being bent into the desired shape.

The tray shown in the drawings comprises a continuous open main frame 7, a clamping frame 8 and woven wire bottom 9. The main frame 7 is preferably made from a continuous strip of sheet metal rolled into a strip 10 (see Fig. 5) substantially channel shaped in cross section and bent to the desired contour as hereinafter mentioned.

At the side margins of the strip are sheet metal flanges 11 and 12 which project outwardly at right angles from the same face

of the strip, thus forming an outwardly facing longitudinal groove or channel 13. The longitudinal side flange 11 projects a greater distance from the body portion of the strip than the opposite flange 12, and is rebent 60 inwardly substantially parallel with the body of the strip, as at 14, and terminates in a flange 15 which is inclined obliquely outwardly away from the body portion of the strip. While the sheet metal strip is 65 still straight, a flat bar 16 is placed in the groove or channel formed in the strip 10 and is spot-welded at intervals to said strip as indicated at 17 in Fig. 5 of the drawing. The outer surface of the bar terminates flush 70 with the longitudinal side flange 12 of the strip thus leaving a space between the rebent portion 14 of the side flange 11 and the outer face of the bar 16. The bar 16 is of the same length as the strip 10 and is positioned therein so as to project a suitable distance beyond one end of the strip and to terminate short of the strip the same distance at its opposite end leaving a space or pocket 18. The main frame 7 is formed by 75 bending the strip and bar into the desired shape, which is preferably rectangular, the opposite ends of the strip and bar being brought together at one side so as to abut. This bringing of the opposite ends of the 80 strip together causes the projecting end of the bar 16 to enter the space or pocket 18 in the opposite end of the strip. The abutting ends of the strip are preferably butt-welded; and likewise the abutting ends of 85 the bar are butt-welded, the lines of the two welds being offset from each other.

The clamping frame 8 is made from a continuous strip of sheet metal rolled or shaped into a strip 19 (see Fig. 6) of substantially 90 angular section. The longer leg of the angle-shaped strip 14 is provided with a V-shaped rib 20 adjacent to its outer margin. The clamping frame 8 is formed by bending the strip 19 into a shape corresponding to 95 that of the main frame 7, the opposite ends of said strip being brought together and butt-welded.

In assembling the parts of the tray, the main frame 7 is placed bottom side up (that 100 is with the rebent flange 14 lowermost) as shown in Fig. 4 of the drawing. A woven wire fabric, which is larger than the main frame and of a shape corresponding to that of the main frame, is then laid over the 110

frame, and then the clamping frame 8 is positioned over the woven wire fabric with its longer, ribbed leg extending downwardly. The clamping frame is then forced downwardly, the lower end of the ribbed leg engaging the woven wire fabric, stretching the wire fabric over the frame 8 and forcing its wire fabric over the frame 8 and forcing its margin downwardly alongside of the flat bar 16 of the main frame 7 until the lower angle of the V-shaped rib 20 on the longer leg of the clamping frame 8 seats against the outwardly inclined flange 15 of the main frame 7. This forcing of the clamping frame over the main frame firmly clamps the margin of the wire fabric between the outer face of the main frame and the inner face of the clamping frame. While the clamping frame is frictionally held in place on the main frame by being forced over the same it may be additionally held in place by screws 21 which extend through the clamping frame and wire bottom, and are threaded into the main frame 8, one screw being placed on each side of the frame. At the welded joints it is preferable to locate a screw on each side of the joint for strengthening purposes.

Some of the principal advantages of a fruit tray constructed in accordance with the foregoing description are its great simplicity; its cheapness of manufacture; its great economy of materials; and the facility it affords for repair and replacement.

What I claim is:

35 1. A fruit tray comprising an open main frame having an outwardly extending top portion, said portion having a groove in its underside, an openwork bottom extending across the bottom of said frame and having its marginal portions turned up along the outside face of the frame, and a frame arranged outside of said main frame with its upper margin extending into said groove and clamping the marginal portions of the openwork bottom to said main frame.

40 2. A fruit tray comprising an open main frame having an outwardly projecting top portion, said portion having a groove in its under side, an openwork bottom extending across the bottom of said frame and having its marginal portions turned up along the outside face of the frame, and a frame of angular section having a continuous rib formed therein, said frame being arranged outside of said main frame with its upper margin extending into said groove and clamping the marginal portions of the openwork bottom to said main frame, and means for securing said clamping frame to said main frame.

45 3. A fruit tray comprising an open main frame having an outwardly extending top portion, said portion having in its under side a groove whose outside wall inclines outwardly and downwardly, an openwork bot-

tom extending across the bottom of said frame and having its marginal portion turned up along the outside face of the frame, and a frame for clamping the margin of said bottom to the frame, said clamping frame being adapted to embrace the outside and bottom of said main frame and having its upper margin extending into said groove.

4. A fruit tray comprising an open main frame having an outwardly extending top portion, said portion having a groove in its under side, the outside wall of which is inclined outwardly and downwardly, an openwork bottom extending across the bottom of said main frame and having its marginal portion turned up along the outside face of the frame, and a frame of angular section for clamping the margin of said bottom to the frame, said clamping frame being adapted to embrace the outside and bottom of the main frame and having a rib formed therein adjacent to its upper margin, the upper portion of said clamping frame extending into the groove formed in the outwardly extending portion of the main frame and the rib adjacent thereto being adapted to bear against the inclined wall of said groove, and means for securing said clamping frame to said main frame.

5. A fruit tray comprising a continuous wall member having a channel formed in its outer side, a bar located in said channel, the portion of the wall member located above the channel extending outwardly beyond the outside face of said bar and having a continuous groove formed in its under side, an openwork bottom having its marginal portions extending upward alongside of said bar, and a clamping member for securing the upturned margins of said bottom to the wall member of the tray, said clamping frame having its upper margins located in the groove formed in the outwardly extending portion of the wall member of the tray.

6. A fruit tray comprising a strip of sheet metal of channel section, a bar located in the channel thereof and arranged to project beyond said strip at one end and to terminate short of said strip at the opposite end, the upper portion of said strip of metal extending outward beyond said bar and being bent down beyond the outside face of said bar to form a continuous groove, said strip and bar being bent into a continuous frame, an openwork bottom having its marginal portions extending upward alongside of said bar, and a clamping member for securing the upturned margins of said bottom to said continuous frame.

7. A fruit tray comprising an open main frame formed of a continuous strip of sheet metal having a channel formed therein, a bar located in said channel, the upper por-

tion of said strip of metal extending outward beyond said bar and being bent down beyond the outside face of said bar to form a continuous groove, an openwork bottom 5 having its marginal portions extending upward alongside of said bar, and a clamping member for securing the upturned margins

of said bottom to the main frame, the upper margin of said clamping frame being adapted to extend into said groove.

Signed at St. Louis, Missouri, this 27 day 10 of September, 1918.

ALFRED M. LANE.
